UNITED STATES PATENT OFFICE.

FRED E. BRADFIELD, OF DAVENPORT, IOWA.

DESIGN FOR A FENDER.

57,579.

Specification for Design.

Patented Apr. 26, 1921.

Application filed October 20, 1919. Serial No. 332,115. Term of patent 7 years.

To all whom it may concern:

Be it known that I, FRED E. BRADFIELD, a citizen of the United States, residing at Davenport, in the county of Scott, State of Iowa, have invented a new, original, and ornamental Design for Fenders, of which the following is a specification, reference being had to the accompanying drawing, forming part thereof.

In the drawing:

Figure 1 is a top view of a fender for an automobile, showing my new design;

Fig. 2 is a side view of the fender shown in Fig. 1;

Fig. 3 is a fragmentary view showing an end portion of the fender; and

Fig. 4 is a perspective view of the fender. A indicates the body portion of the fender. This body portion is curved longitudinally and at its edges is provided with bevel portions B that slope outwardly and downwardly from the longitudinal central part of said body portion, such beveling constituting the characteristic feature of this design.

I claim;

The ornamental design for a fender substantially as shown and described.

FRED E. BRADFIELD.
